WASHTUB STAND

Filed Aug. 13, 1929

FIG. 1

FIG. 2

FIG. 3

HANS LINDELOF
INVENTOR

PER *Gust. Fjelde*
ATTORNEY

UNITED STATES PATENT OFFICE

HANS LINDELÖF, OF DE KALB, ILLINOIS

WASHTUB STAND

Application filed August 13, 1929. Serial No. 385,521.

This invention relates to improvements in washtub stands and has for one of its principal objects the provision of a stand for washtubs which can be readily associated

5 with an ordinary washing machine in such a way that a plurality of tubs may be grouped at a convenient height around the washing machine for receiving clothes in various stages of the washing process.

10 One of the important objects of this invention is to provide in a washtub stand a simple unitary construction which is economical of manufacture, durable in operation, and of sufficient strength to meet all needs.

15 Another and still further important object of this invention is to provide a washtub stand, means for supporting tubs adjacent a washing machine which means shall be readily applicable to any make of washing

20 machine now on the market.

Other and further important objects of this invention will be apparent from the disclosures in the drawings and following specification.

25 The invention in a preferred form is illustrated in the drawings and hereinafter more fully described.

In the drawings:

Figure 1 is a top plan view of the improved 30 washtub stand of this invention.

Figure 2 is a side elevation showing one of the supporting lugs.

Figure 3 is a detail view illustrating the reinforcing braces for the lugs.

35 Figure 4 is a sectional view taken on the line 4-4 of Figure 1 looking in the direction indicated by the arrows.

As shown in the drawings:

The reference numerals 10 indicate generally the top supporting element of the improved washtub stand of this invention, this element being preferably composed of a strip of metal or the like of suitable weight to support the tub placed thereon. Obviously, the size and capacity of the stand may be varied without departing from the principles of the invention.

It will be noted that the tub member 10 has two portions thereof bent into the shape of arcs of circles preferably concentric as shown

at 12 and that the member is closed upon itself to form a four sided figure, two or more of which may be joined to complete the stand.

Each of the frames 10-12 is supported by 55 a plurality of uprights or legs 14 which also are composed of strip metal, each strip being bent double upon itself and rounded at the bottom as shown at 16 to provide a suitable footing which is readily slideable from place 60 to place.

These legs 14 are bolted or riveted to downwardly extending brackets or braces 18, the bolt or rivet forming a pivotal point as shown at 20.

65 At the top of each leg 14 and at the point where it joins the member 12, there is drilled an opening for the reception of the bolt of a thumbscrew or the like 22 which passes through a similar opening formed in the 70 member 12. Each of the legs 14 has a corresponding leg at the rear of the device as best shown in Figure 3, these legs being joined by means of cross pieces or reinforcing braces as best illustrated at 24.

75 It will be noted that the two sections 10-12 are connected together by means of bolts or the like 26 passing through aligned openings in the ends of the members 10-12. In this way, a stand of any desired dimensions can be built up.

It will be noted that when the thumbscrews 22 are removed, the legs 14 can be tilted about their pivotal attachments 20 to the position shown in the dotted line in Figure 2 whereby the stand may be made more compact for purposes of ready and convenient transportation from place to place if desired or necessary.

At the point of juncture between the elements 10 is positioned an extra downwardly extending leg 30 which is held in position by means of a bolt and nut or the like 32 and is riveted to a corresponding angularly extending bracket 34, the upper end of this bracket 95 member being in turn removably bolted in position between the members 10 as best illustrated in Figure 1. This additional leg at the forward portion of the device provides for greater stability.

It will be obvious that herein is provided a washtub stand which is of simple construction and therefore readily operated and not at all likely to get out of order. Further, it is portable and can be conveniently transported from place to place. Obviously, when the legs 14 are folded up under the device, the leg 30 can be either removed or also folded up by removing the bolt 36 at the point of juncture between the bracket 34 and the members 10.

I am aware that many changes may be made and numerous details of construction varied throughout a wide range without departing from the principles of this invention, and I therefore do not purpose limiting the patent granted hereon otherwise than as necessitated by the prior art.

I claim as my invention:

- 20 A washtub stand for compact arrangement of tubs and washing machine comprising in combination, a framework having front and rear edges in the form of arcs of circles and with straight ends, a plurality of supporting legs, rivets and bolts joining, a plurality of such frameworks together to form a stand of lesser rear lineal dimension than frontal dimension, the forward supporting legs being pivotally mounted to
- 25 30 downwardly extending braces at the edges of the frames, together with brackets extending rearwardly to companion supporting legs at the rear ends of the frames.

In testimony whereof I affix my signature.

35

HANS LINDELOF.
